(57) **CLAIM**

The ornamental design for a dog boot, as shown and described.

DESCRIPTION

FIG. 1 is a perspective view of a dog boot showing the design.

FIG. 2 is a side view thereof.

FIG. 3 is an opposite side view thereof.

FIG. 4 is a front view thereof.

FIG. 5 is a back view thereof.

FIG. 6 is a top view thereof; and,

FIG. 7 is a bottom view thereof.

The design is for a dog boot which is used to protect feet and pads from glass, nails, barbed wire, needles and other harmful objects.
